UNITED STATES PATENT OFFICE.

JOHN O. NEIKIRK, OF LOMBARD, ILLINOIS.

CAR CONSTRUCTION.

1,405,544.

Specification of Letters Patent. Patented Feb. 7, 1922.

Application filed February 14, 1921. Serial No. 444,879.

To all whom it may concern:

Be it known that I, JOHN O. NEIKIRK, a citizen of the United States, residing at Lombard, in the county of Du Page and State 5 of Illinois, have invented certain new and useful Improvements in Car Constructions, of which the following is a specification.

This invention relates to railway cars and particularly to the end construction of such 10 cars, and has for its object to provide an end construction in which the blows and stresses imparted to the striking plate will be transmitted directly to the frame members of the car and effectively and more adequately distributed thereto.

In carrying out my invention I provide an end sill member and draft sills and an integral striking plate casting, these parts being so arranged and interconnected as to 20 effectively carry out the above stated objects of my invention.

In the accompanying drawing—

Figure 1 is a front view of a portion of the end of a car, showing various members 25 of the car frame and striking plate casting arranged in accordance with my invention.

Figure 2 is a section on the line 2^x—2^x of

Figure 1; and

Figure 3 is a plan view, partly in section, 30 on the line 3^x—3^x of Figures 1 and 2.

A represents a pair of oppositely disposed spaced channel irons constituting the draft sills of a railway car and having upper and lower flanges A' and A². B represents the 35 end sill of the car which may be constructed of a central web or plate with angle iron base flanges B' and B² which bridge the space between the draft sills A and as shown in the present example rest upon the cover 40 plate B³ of the draft sills. These parts may be of any approved construction. As shown, the draft sills extend outwardly beyond the end sill.

C represents a combined striking plate and 45 carry iron which is an integral member produced by casting or forging. One feature of the member C consists in a top wall C' composed of an inner horizontally extending leg C¹¹ constituting the upper face of the 50 coupler shank opening, a parallel inwardly extending outer leg C¹² and a vertical striking face C¹³ which connects the legs C¹¹, C¹² and spaces them apart. Legs C¹¹, C¹² may be further spaced apart and strengthened by 55 the horizontally extending vertical webs C¹⁴ in the same vertical plane with the side walls

in position to lie against the inner faces of the draft sills A, and one or more intermediate horizontally extending webs C¹⁵. The inner leg C¹¹ extends only for the horizontal dimension of the coupler shank opening, but the upper leg C¹² is longer and extends between the spacing webs C¹⁴, C¹⁵ a distance sufficient to overlap the base flanges B' of the end sill B and the horizontal flanges A' 60 of the draft members A, although it will be understood that this member may underlie said end sill flange, if so desired. It is secured by rivets C¹⁶ to both the end sill flange B' and draft sill flanges A', and by intermediate rivets C¹⁷ to that portion of the end sill flange B' which bridges the space between the draft sills, and also the bridging portion of the cover plate B³ when the latter is employed. Another feature of the member C is its side walls C² composed of inwardly extending vertical flanges C²¹ and laterally extending vertical flanges C²². Flanges C²¹ constitute the lateral confines of the shank opening, and they are preferably 70 made to abut against the draft lugs E riveted to the inner faces of the draft sills A². The flanges C²¹ are riveted to the webs of the draft sills by means of the flat headed rivets C²³ within the shank opening, and by additional rivets C²⁴ below the horizontal wall of the shank opening. A further feature of the member C consists of the bottom wall C³ composed of the inwardly extending horizontal flange C³¹ and the downwardly extending vertical flange C³², which strengthens the flange C³¹ and affords a rigid and safe 80 carry iron integral with the side walls C².

From the above description it will be seen that I have provided a car end construction 95 in which the frame members of the car are so connected together, through the medium of the striking plate casting, that the strains imposed upon the casting will be transmitted, through the rivets connecting the casting 100 to the frame members, directly to said members and also that these strains will be resisted by the rivets connecting the draft lugs to the draft sills, and that these strains are transferred to both longitudinal and transverse members of the frame, these parts being rigidly connected together by the fastenings connecting them to the striking plate casting. It will be further seen that by the 105 employment of an integral striking plate casting and carry iron, such as I have shown, the frame members, as above described, are 110

strongly reenforced and it will be further noted that the members of the casting are generally of angle shape giving the greatest possible strength with the least amount of metal and that owing to this shape of the lower horizontal portion of the casting forming the carry iron I am enabled to advantageously place the lower rivets in the said members of the casting to connect them to the draft sill members. It is further apparent that it is possible in this structure to form the opening in the casting of the proper dimensions to receive the standard coupler shank and support it at the standard height and with the standard side clearance without the use of any additional parts.

Having now described my invention, what I claim and desire to secure by Letters Patent, is:

- 20 1. A railway car comprising draft sills having flanged upper edges, an end sill having a flanged lower edge, the ends of said draft sills extending beyond the end sill, an integral striking plate casting and carry iron having upper, lower and side flanges surrounding an opening receiving the coupler shank, means securing an upper flange of the casting to the flanges of the end sill and draft sill, and separate means securing 30 said upper flange to the flange of the end sill.
2. A railway car comprising draft sills having flanged upper edges, an end sill having a flanged lower edge, an integral striking 35 plate casting and carry iron having upper,

lower and side flanges surrounding an opening receiving the coupler shank, common means securing said upper flange of the casting to the draft sill and end sill flanges, and means separately securing said upper flange 40 of the casting to the flanges of the draft sills.

3. A railway car comprising draft sills having flanged upper edges, an end sill having a flanged lower edge, said draft sills extending beyond the end sill, an integral 45 striking plate casting and carry iron having upper, lower and side flanges, said flanges surrounding an opening to receive the coupler shank and supporting said shank at the standard height and with the standard side 50 clearance, means securing an upper flange of the casting to the flanges on the ends of the draft sills, beyond the end sill, and common means securing said upper flange of the casting to the flanges of the end sill and the 55 draft sills, means securing the side flanges of the casting to the sides of the draft sills.

4. A railway car comprising draft sills, an end sill having an outwardly extending flanged lower edge secured to the upper 60 faces of the draft sills, an integral striking plate casting and carry iron having an upper flange extending inwardly toward the flange of the end sill; said end sill flange and casting flange being arranged to overlap, and 65 means for securing said end sill flange and casting flange together.

Signed at Chicago, Ills.; this 3rd day of February, 1921.

JOHN O. NEIKIRK.
